LIGHT REFLECTING STUD

Howard B. Wood, New York, N. Y., assignor to
 Lumelite Corporation, New York, N. Y., a corporation of New York

Application August 23, 1940, Serial No. 353,831

9 Claims. (Cl. 88—82)

This invention relates to light-reflecting studs for use in signs and producing multi-colored effects when light rays impinge thereon.

The nature and objects of this invention will become clear from the following description, appended claims and accompanying drawing forming a part of this specification and wherein:

Figure 1 is a plan view of an illustrative sign embodying and containing the principles of this invention;

Figure 2 is an enlarged plan view of a reflecting stud embodied and utilized in the sign shown in Figure 1;

Figure 3 is a section taken on the line 3—3 of Figure 2;

Figure 4 is an expanded view showing the details of construction of the light-reflecting studs; and

Figure 5 is a plan view of the multi-colored light produced by a light-reflecting stud.

The studs constituting this invention are so designed and constructed that, when arranged and secured to a sign panel and light rays from any source impinge on the front thereof, multi-colored effects will be visible to an observer viewing the sign from the front thereof. The studs are also so constructed and designed that, when arranged and secured to a sign panel and light rays from any source impinge on the rear surface of the sign, multi-colored effects or an annular ring effect will be visible to an observer viewing the sign from the front thereof.

In order to more fully explain the nature of the invention, reference will now be had to the accompanying drawing wherein like reference numerals designate like parts and wherein the reference numeral 1 designates generally a sign comprising a panel 5 having light-reflecting studs 6 arranged and positioned in accordance with the desired indicia. In the form shown in Figure 1, the indicia are represented for illustrative purposes by the word "Sign." It is to be understood that the indicia are not restricted to the precise indicia illustrated, since it is obvious that the indicia may be any desired word or words, character or characters, figures, etc.

The panel 5 may be formed of any desired material. Generally, the ultimate use of the sign 1 determines the nature of the material constituting the panel. Thus, if the sign is intended for outdoor use, as, for example, a road marker, then the panel 5 may be made of a material, such as sheet metal, plastic, or the like, which is resistant to the elements of the weather. On the other hand, if the sign is to be used indoors,

then the panel 5, though it can be made of a weather resistant material, need not be made thereof but may be made of any other suitable material.

5 In order to enhance the appearance of the sign 1, the panel 5 may be appropriately decorated. For example, the panel 5 may be provided with an appropriately colored or multi-colored coating. If desired, though it is not essential, the 10 indicia may also be delineated by an appropriate colored coating, such as is generally indicated by the reference numeral 8. The colors of the panel coating and/or the indicia are preferably contrasting and of a hue which will tend to 15 intensify the multi-colored effects given off by the studs when the sign is illuminated.

The construction of the light-reflecting studs 6 is an important feature of this invention. In one embodiment of the invention, each stud 6 comprises a head 10 having a rearwardly extending hollow skirt 11. The head 10 is preferably solid and rounded (semi-spherical), as shown in the drawing. The skirt 11 is preferably made integral with the head 10 and is so positioned with respect to the rear flat face of the head as to provide the stud 6 with a circumferential shoulder 12 for the reasons which will become apparent hereafter. The skirt 11 is furthermore made of such length that it will project from 30 the rear of the sign.

In the interior of the hollow skirt 11 there is provided a cylindrical insert 15 which is preferably of such a size that the top and the side walls thereof fit snugly and flush with the flat rear face of the head 10 and the inner wall of the skirt 11, with which it engages. The bottom face 16 of the insert 15 is made concave for reasons which will hereafter appear. A light-reflecting element 17 is disposed within the skirt 11 and positioned in cooperative relationship with respect to the concave surface 16 so that the light rays passing through the insert 15 will be reflected thereto by said reflecting element 17. In the form shown, the reflecting element 17 is provided with a concave reflecting surface 18 and with teeth 19, whereby it may be locked into position within the hollow skirt 11. The locking of the reflecting element 17 into position also serves to secure the insert 15 in position.

50 The material or materials of which the head 10, the skirt 11 and the insert 15 are made should be such as will transmit both incident and reflected rays of light without substantially dispersing said rays of light. In addition, the material should present pleasing and non-glaring

effects when illuminated. Acrylate resins, and particularly that acrylate resin sold under the trade-name "Lucite," possess the aforementioned properties and characteristics to a very high degree and, accordingly, in the preferred form of the invention, the head 10, the skirt 11 and the insert 15 are formed of an acrylate resin, specifically that acrylate resin sold under the trade-name of "Lucite." To secure the desired multi-colored effects, the insert 15 is made of a color different from the color of the head 10 and the skirt 11.

The reflecting element 17 is preferably made of metal, the concave surface 18 thereof being provided with a reflecting surface.

In the construction of the sign, the selected sign panel, decorated as previously described, is provided with a plurality of holes arranged in accordance with the desired indicia. In each of the holes there is inserted a stud 6, previously assembled, and including the insert 15 and the reflecting element 17. Each stud 6 is inserted in one of the holes so that the shoulder 12 of the stud is flush with the front surface of the panel 5, whereby the holes in the panel are concealed from view. Various means may be utilized to lock and secure the stud in place in the panel. In the form shown, this is secured by means of a lock washer 20 which is positioned on the skirt 11, as shown in Figure 3. The lock washer 20 is normally concave and is provided with teeth 21 whereby, when it is positioned on the skirt 11 and flattened, the teeth 21 will grip the skirt 11 and thereby securely lock the stud in position.

When light rays impinge on the front face of the sign, the light rays will be transmitted through the head 10. The light rays impinging on the head opposite to the skirt 11 will pass through the skirt and be visible to an observer as an annular ring of light. The light rays penetrating the head 10 in juxtaposition to the insert 15 will also pass therethrough and, after impinging on the reflecting surface 18 of the reflecting element 17, will be reflected therefrom and pass through the insert 15, and the head 10 will be visible to an observer as a circle of light having a color substantially the same as the insert. Because of the construction of the stud, there will become visible a circle of light having an annular ring surrounding a differently colored field of light. If the head 10 and the skirt 11 are made of, for example, clear, transparent, colorless "Lucite" and the insert 15 is made of, for example, transparent red colored "Lucite," the stud 6 will, when light rays impinge on the head 10, present to view a circle of light having a two-tone color effect, and specifically a ring of white (colorless) light 25 surrounding a field of red light 26, such as is illustrated in Figure 5.

If light rays impinge on the rear of the sign panel, the light will penetrate through the skirt 11 and through the head 10 and form a ring of white (colorless) light. If no light rays penetrate the insert 15, then the ring of the visible white light will appear hollow, thereby also producing a two-tone effect.

If desired, the insert 15 may be made of two or more colors, with the result that the circle of light visible to an observer may consist of a plurality of contiguous rings of differently colored light surrounding a solid field of light. Also, if desired, the multi-colored effects of selected studs may be made different by using differently colored inserts.

The studs hereinbefore described are particu-

larly useful in the manufacture of road markers. By virtue of the multi-colored, and specifically the two-tone, effects produced, they are not only visible but also are highly attractive, with the result that they immediately attract the attention of, for example, an automobile driver.

A sign containing the light-reflecting studs embodied by this invention may be utilized wherein light rays are caused to impinge on the front face of the sign by any appropriate means, for example, a source of light, such as an incandescent lamp and a reflector directing the light rays onto the sign. If desired, the source of illumination may be positioned to cause the light rays thereof to impinge on the rear on the panel. Alternatively, the source of light may be provided to cause light rays to impinge alternately on first the front, and then the rear face of the sign.

Since it is obvious that various changes and modifications may be made in the above description without departing from the nature or spirit thereof, this invention is not restricted thereto except as set forth in the appended claims.

I claim:

1. A reflecting stud adapted to be positioned in an aperture formed in a panel and comprising a head permitting the passage of light rays therethrough and adapted to be exposed on the front surface of said panel, said head having a circumferential shoulder adapted to be seated on the front face of the panel, a hollow skirt permitting the passage of light rays therethrough and extending from the rear face of said head, and means to permit the passage of light rays impinging on the rear of the stud through the wall of said skirt only and present a ring of light to an observer.

2. A reflecting stud adapted to be positioned in an aperture formed in a panel and comprising a head permitting the passage of light rays therethrough and adapted to be exposed on the front surface of said panel, said head having a circumferential shoulder adapted to be seated on the front face of the panel, a hollow skirt permitting the passage of light rays therethrough and extending from the rear face of said head, and means in the hollow of said skirt to inhibit the passage of light rays impinging on the rear thereof, whereby light rays impinging on the rear of the stud will be visible to an observer as a ring of light.

3. A reflecting stud adapted to be positioned in an aperture formed in a panel and comprising a head permitting the passage of light rays therethrough and adapted to be exposed on the front face of said panel, said head having a circumferential shoulder adapted to be seated on the front face of the panel, a hollow skirt permitting the passage of light rays therethrough and extending from the rear face of said head, said skirt being adapted to pass through said aperture and project from the rear face of said panel, the light rays passing through the wall of said skirt being visible to an observer as a ring of light, means within the hollow of said skirt to reflect light rays passing through said head and incident thereon, and means within the hollow of said skirt to color said reflected light rays, said reflected light rays being visible to an observer as a field of colored light within said ring of light.

4. A reflecting stud adapted to be positioned in an aperture formed in a panel and comprising a head permitting the passage of light rays therethrough and adapted to be exposed on the front face of said panel, said head having a circum-

ferential shoulder adapted to be seated on the front face of the panel, a hollow skirt permitting the passage of light rays therethrough and extending from the rear face of said head, said skirt being adapted to pass through said aperture and project from the rear face of said panel, the light rays passing through the wall of said skirt being visible to an observer as a ring of light, a colored insert permitting the passage of light rays therethrough positioned in the hollow of said skirt, and means within the hollow of said skirt and below said insert to reflect light rays incident thereon through said insert, said reflected light rays being visible to an observer as a field of light within said ring of light.

5. A reflecting stud adapted to be positioned in an aperture formed in a panel and comprising a head permitting the passage of light rays therethrough and adapted to be exposed on the front face of said panel, said head having a circumferential shoulder adapted to be seated on the front face of the panel, a hollow skirt permitting the passage of light rays therethrough and extending from the rear face of said head, said skirt being adapted to pass through said aperture and project from the rear face of said panel, the light rays passing through the wall of said skirt being visible to an observer as a ring of light, an insert permitting the passage of light rays therethrough positioned in the hollow of said skirt, and means within the hollow of said skirt and below said insert to reflect light rays incident thereon through said insert, said insert being of a color different from said head and skirt, said reflected light rays being visible to an observer as a field of light within said ring of light.

6. A reflecting stud adapted to be positioned in an aperture formed in a panel and comprising a head permitting the passage of light rays therethrough and adapted to be exposed on the front face of said panel, said head having a circumferential shoulder adapted to be seated on the front face of the panel, a hollow skirt permitting the passage of light rays therethrough and extending from the rear face of said head, said skirt being adapted to pass through said aperture and project from the rear face of said panel, the light rays passing through the wall of said skirt being visible to an observer as an annular ring of light, an insert permitting the passage of light rays therethrough positioned in the hollow of said skirt, a reflector in the hollow of said skirt and below said insert to reflect light rays incident thereon to said insert, said reflected light rays being visible to an observer as a field of light within said ring of light, and means to secure said reflector in position in said skirt.

7. A reflecting stud adapted to be positioned in an aperture formed in a panel and comprising a head permitting the passage of light rays therethrough and adapted to be exposed on the front face of said panel, said head having a circumferential shoulder adapted to be seated on the front face of the panel, an annular skirt permitting the passage of light rays therethrough

and extending from the rear face of said head, said skirt being adapted to pass through said aperture and project from the rear face of said panel, the light rays passing through the wall of said skirt being visible to an observer as a ring of light, a colored insert permitting the passage of light rays therethrough positioned in the hollow of said skirt, and a metallic reflector in the hollow of said skirt and below said insert to reflect light rays incident thereon to said insert, said reflected light rays being visible to an observer as a field of light within said ring of light, said reflector having teeth along its peripheral edge to engage the inner wall of said skirt to lock said reflector in position.

8. A reflecting stud adapted to be positioned in an aperture formed in a panel and comprising a head permitting the passage of light rays therethrough and adapted to be exposed on the front face of said panel, said head having a circumferential shoulder adapted to be seated on the front face of the panel, a hollow skirt permitting the passage of light rays therethrough and extending from the rear face of said head, said skirt being adapted to pass through said hole and project from the rear face of said panel, the light rays passing through the wall of said skirt being visible to an observer as a ring of light, an insert permitting the passage of light rays therethrough positioned in the hollow of said skirt, a reflector in the hollow of said skirt and below said insert to reflect light rays incident thereon to said insert, said reflected light rays being visible to an observer as a field of light within said ring of light, and means to secure said reflector in position in said skirt, said head, skirt and insert being made of "Lucite," said insert being of a color different from said head and skirt.

9. A reflecting stud adapted to be positioned in an aperture formed in a panel and comprising a head permitting the passage of light rays therethrough and adapted to be exposed on the front face of said panel, said head having a circumferential shoulder adapted to be seated on the front face of the panel, a hollow skirt permitting the passage of light rays therethrough and extending from the rear face of said head, said skirt being adapted to pass through said aperture and project from the rear face of said panel, the light rays passing through the wall of said skirt being visible to an observer as a ring of light, an insert permitting the passage of light rays therethrough positioned in the hollow of said skirt, and a metallic reflector in the hollow of said skirt and below said insert to reflect light rays incident thereon to said insert, said reflected light rays being visible to an observer as a field of light within said ring of light, said reflector having teeth along its peripheral edge to engage the inner wall of said skirt to lock said reflector in position, said head, skirt and insert being made of "Lucite," said insert being of a color different from said head and skirt.

HOWARD B. WOOD.

CERTIFICATE OF CORRECTION.

Patent No. 2,317,162.

April 20, 1943.

HOWARD B. WOOD.

It is hereby certified that error appears in the printed specification of the above numbered patent requiring correction as follows: Page 3, first column, line 20, claim 5, for "fact" read --face--; and that the said Letters Patent should be read with this correction therein that the same may conform to the record of the case in the Patent Office.

Signed and sealed this 25th day of May, A. D. 1943.

Henry Van Arsdale,
(Seal) Acting Commissioner of Patents.
